SIGN OR SIMILAR ARTICLE

Ted Doss, El Paso County, Colo., assignor to Harold L. Michaelis, Colorado Springs, Colo.

Filed July 1, 1963, Ser. No. 75,608

Term of patent 14 years

(Cl. D1—12)

FIG. 2.

FIG. 1.

FIG. 3.

FIGURE 1 is a perspective view taken from one side of a sign or similar article showing my new design, the opposite side being a mirror image of the side shown.

The vertical lines on the left standard as illustrated in FIGURE 1 represent a lined pattern.

I claim:

The ornamental design for a sign or similar article, as shown and described.
